BOOTH UNIT FOR A LOUNGE OR THE LIKE

Billy Joe Walters, 1916 "B" Demer Road,
St. Simons Island, Ga. 31522

Filed May 26, 1969, Ser. No. 17,326

Term of patent 14 years

Int. Cl. D6—01

U.S. Cl. D80—2

FIG. 2

FIG. 1 is a side elevational view of a booth unit for a lounge or the like embodying my new design, the repeat portion of the design indicated by dot-dash lines; and

FIG. 2 is a perspective view thereof.

I claim:

The ornamental design for a booth unit for a lounge or the like, as shown and described.
